UNITED STATES PATENT OFFICE.

GEORGE A. LONG, OF ANTWERP, OHIO, ASSIGNOR OF ONE-HALF TO HENRY HARRIS, OF SAME PLACE.

COMBINATION CART AND CHAIR.

SPECIFICATION forming part of Letters Patent No. 674,783, dated May 21, 1901.

Application filed December 20, 1900. Serial No. 40,486. (No model.)

To all whom it may concern:

Be it known that I, GEORGE A. LONG, a citizen of the United States, residing at Antwerp, in the county of Paulding and State of Ohio, have invented certain new and useful Improvements in a Combination Cart and Chair; and I do hereby declare the following to be a full, clear, and exact description of the invention, such as will enable others skilled in the art to which it appertains to make and use the same.

My invention relates to wheeled toys, but more particularly to a combination cart and chair, and has for one object to provide an apparatus of this class which can be used either as a rocking-chair or cart.

A further object of my invention is to provide a toy of this class which is cheap to manufacture, simple in operation, and above all strong and durable.

With these objects in view my invention consists in the combination and novel arrangement of a rocking-chair provided with wheels and a tongue.

My invention also consists in other novel features of construction, which will be hereinafter fully described and afterward more particularly pointed out in the appended claims.

Referring to the accompanying drawings, Figure 1 is a perspective view of my combined rocking-chair and cart. Fig. 2 is a sectional view of the same, showing tongue attached and in the position when being used

as a cart. Fig. 3 is a sectional view on the same lines as Fig. 2, showing tongue detached and in the position when being used as a rocking-chair. Fig. 4 is a perspective view of my improved form of tongue.

Like letters of reference indicate like parts throughout the several figures, in which—

A is the body, B the legs, and C the rockers. Directly under the front edge of the bottom or seat *a* of the body A is a cross-piece D, provided with the slot E. Directly under said cross-piece and above the step F is a similar cross-piece G, having a similar slot or notch H. Underneath the bottom or seat *a* and in line with and in rear of the slot E and notch H is the hollow triangular boxing I, composed of triangular sides and the bot-

tom K. The frame L, pivoted to the rockers C at M, carries the axle N, on which are journaled the wheels O in any approved manner. The cross-piece P of the frame L is situated between the notch H and the boxing I.

Q is the tongue, provided with the triangular portion R and the notch S and the flat portion T, which is substantially parallel to the top of the triangular body R, and it will be noticed that said triangular body and the tongue proper form an angle of about one hundred and sixty degrees.

Having thus described the several parts of my invention, its operation is as follows: When it is desired to use my device as a rocking-chair, the tongue is not employed and the chair rests on its rockers, as shown in Fig. 3. When it is desired to convert the chair into a cart, the triangular body R of the tongue is inserted in the slot E and notch H and passes into the triangular boxing I. This operation pushes the cross-bar P downwardly, thus throwing the tread of the wheels O to a point below the rockers C. When the triangular body R is thus inserted, the cross-bar P slips into the notch S in the tongue and the flat portion T rests in the notch H in the cross-piece G, and the weight of the cart holds the tongue and cross-bar P in engagement. When it is desired to disengage the tongue, the cart is lifted and the cross-bar P drops out of the notch S and the tongue is drawn out.

Having thus specifically described the operation of my invention, I do not wish to be understood as limiting myself to the exact construction herein set forth, as various slight changes might be made therein which would fall within the limit and scope of my invention, and I consider myself entitled to all such changes and modifications.

What I claim as new, and desire to secure by Letters Patent of the United States, is—

1. The combination of a chair, wheels secured thereto, and a tongue adapted to be attached thereto, and securely held by the weight of the chair, substantially as described.

2. The combination of a chair, the hollow boxing, wheels secured to said chair, and a

tongue adapted to enter said boxing, and be securely held by the weight of the chair, substantially as described.

3. The combination of a chair, a hollow boxing, a frame pivoted to the rockers of said chair, wheels carried by said frame, and a tongue adapted to enter said boxing, and be securely held therein by the weight of the chair on the cross-bar of said frame, substantially as described.

4. The combination of a chair and cart, a hollow boxing secured to the seat or bottom thereof, a frame pivoted to the rockers of

said chair, wheels carried by said frame, and a tongue adapted to enter said boxing; said tongue having a notch therein, which engages the cross-bar of said frame, and is held in engagement by the weight of the cart, as set forth.

In testimony whereof I affix my signature in presence of two witnesses.

GEORGE A. LONG.
